DEHYDRATOR WITH HIGH FIELD INTENSITY GROUNDED ELECTRODE

Application filed September 16, 1926. Serial No. 135,804.

This invention relates to the art of dehydrating petroleum emulsions and it is embodied in a unique dehydrator.

My invention relates to a dehydrator which is particularly adapted for treating very "wet" emulsions, though it is not limited in utility to the treatment of such emulsions, the treater herein described being capable of treating a wide range of emulsions. In the ordinary dehydrator wet emulsions cannot be economically or successfully treated because of the chaining of the water particles between the electrodes which draws a heavy current and prevents a high potential gradient field from being set up. It is well known that an electric field must be established in order that agglomeration of the water particles will be effected.

It is an object of this invention to provide a dehydrator in which wet emulsion may be economically and successfully dehydrated.

I have found that short-circuiting between the electrodes of the dehydrator may be prevented by forming a dielectric barrier between the wet emulsion and one of the electrodes.

It is an object of the invention to provide a dehydrator in which a dielectric barrier or sheath is formed between the emulsion being treated and one of the electrodes. As a dielectric barrier I may use any substance having the necessary qualities. I find it very satisfactory to use a dry oil for this purpose.

I have found that there is a marked difference in the effectiveness of an electrical dehydrator depending upon the character of the electric treating field and upon the exact part of the field in which the emulsion is treated. By the character of the electric treating field I have reference particularly to the distribution of the potential gradient across the gap between the electrodes of different potential.

By suitable design a dehydrator can be built to provide an electrode of such shape or form that the potential gradient in the treating zone between the two electrodes will not vary uniformly in direct ratio to the distance between the two, but will be greatly concentrated on the surface of one of them, thus

giving rise to an electrode of a higher or maximum field intensity. For example, in the case of a uniform distribution across a gap of two inches between electrodes and across which a potential of 10,000 volts is impressed 55 assume a point situated midway of the two electrodes. The potential difference between this point and either of the two electrodes will be practically one-half of the total impressed difference of potential or 5,000 volts. 60 This is equivalent to an average gradient on either side of the midway point of 5,000 volts per inch.

On the other hand, a point midway between the electrodes separated two inches apart and 65 designed especially for a non-uniform distribution of potential may be caused to have a potential difference between itself and the electrode of lowest field intensity of but 2,000 volts and between itself and the electrode 70 of highest field intensity of 8,000 volts. In this case, the same total difference of potential impressed across the two electrodes will be non-uniformly distributed, and the average distribution for the midway point to the 75 electrode of lowest field intensity will be 2,000 volts per inch, and the electrode of highest field intensity will be 8,000 volts per inch.

If the emulsion is passed at random 80 through this treating space the part which passes through the high intensity field will be treated very effectively, whereas the part which passes through the low intensity field will be treated but very little. It will be seen 85 then that if emulsion is to be efficiently dehydrated in a minimum period of time its passage through the dehydrator's treating space must be determined; therefore, if I introduce the emulsion before treatment into that portion of the field having the maximum field intensity or the highest potential gradient per inch, as already referred to above, it, in general, will pass through the field thoroughly treated. Under these conditions the fluid surrounding or adjacent to the electrode of 90 lowest field intensity, and forming a dielectric barrier around said electrode, is subjected to a relatively lower stress than is the emulsion in the maximum intensity field and 95 100

will not readily rupture, therefore preventing short-circuiting currents between the electrodes and thus maintaining them at the highest possible difference of potential.

5 My experiments have shown that the most efficient treatment of emulsion is received by causing it to follow along or effectually parallel to the electrode of highest field intensity, and to form an envelope around this electrode, this envelope travelling lengthwise over the surface of the electrode of highest field intensity for a distance to effect complete treatment. I find that, in general, this distance is relatively short.

10 15 It is an object of the invention to provide a dehydrator of the nature mentioned in which the emulsion to be treated is directed along the electrode of highest field intensity.

20 It is quite essential to the successful operation of the dehydrator of this invention that the dielectric barrier be maintained and not destroyed by mixing with the emulsion. The dry oil is self-healing and if broken will immediately rejoin. Although good results 25 may be obtained when using an ordinary electrode, I find that all danger of the barrier being broken is removed if the electrode of highest field intensity is formed of a material having an affinity for the emulsion.

30 35 It is another object of the invention to provide a dehydrator of the character mentioned in which the electrode along which the emulsion is directed has a surface formed of a material having an affinity for the fluid moving there adjacent.

40 45 In common types of dehydrators the electrode of highest field intensity is the live or high tension electrode. In my invention I prefer to reverse the standard practice and make the electrode of highest field intensity the grounded electrode. This permits the emulsion inlet to be connected to the electrode of highest field intensity without danger or the use of complicated insulated feeding mechanism.

It is accordingly another object of the invention to provide a dehydrator having a grounded electrode of highest field intensity.

50 Extensive experimenting to determine what action takes place in a dehydrator to cause coalescing of the water particles has revealed and proven that in the electric field especially where the field intensity is high, a stream of charged electrolytic particles (or 55 the water particles) are thrown rapidly from the electrode into the body of emulsion. These charged particles bombard other particles of water in the emulsion joining with them and forming masses which may be separated from the oil by gravity. I have discovered that the discharging of the charged particles from the electrode may be enhanced 60 by providing the electrode with edges from 65 which, it is found, the charged particles will

be rapidly and forcibly shot into the emulsion.

It is an object of the invention to provide a dehydrator in which the charged particles will be actively dispelled from one (or both) 70 of the electrodes.

Another object of my invention is to provide a novel method of treating a fluid such as petroleum emulsion by passing this fluid through a high intensity portion of an electric field. 75

Still a further object of my invention is to provide a method of treating fluids such as petroleum emulsions in which the fluid is passed through an electric field having a non-uniform voltage gradient. 80

Other objects and advantages of the invention will be made evident hereinafter.

Referring to the drawings in which I illustrate my invention.

Fig. 1 is a vertical section through a preferred form of the invention.

Fig. 2 is a section taken on the line 2—2 of Fig. 1.

Fig. 3 is a section taken on the line 3—3 90 of Fig. 1.

Fig. 4 is an enlarged vertical fragmentary section through the central electrode of the apparatus.

Fig. 5 is a fragmentary vertical section 95 showing an alternative form of the invention.

Referring to Figs. 1 to 4 inclusive my invention provides a cylindrical shell 11 provided with a tight top 12 and a tight conical bottom 13. Supported by the top 12 is an insulator 14 through which a high tension conductor 15 is extended. The lower end of the conductor 15 supports a frame structure 16 by means of which a live electrode or a shield 17 is supported in proper position inside the shell 11. Extended centrally upward through the bottom 13 is an emulsion inlet pipe 20. The upper end of the emulsion inlet pipe 20 extends inside the live electrode 17 and serves as a grounded electrode 21.

Referring particularly to Fig. 4, the upper end of the pipe 20 is provided with spacer members in the form of sleeves 22 which are separated by discs 23. The sleeves and discs are formed from a material such as plaster of Paris or certain kinds of cement which have an affinity for the emulsion and thus tend to hold the emulsion thereadjacent. A nut 25 is screwed onto the upper end of the pipe 20 so as to tightly clamp the sleeves and discs 22 and 23 against a sleeve 26 of the pipe 20. The nut 25 carries a dome 28 and is provided with emulsion outlet openings 29. An annular passage 30 connects the openings 29 with the exterior of the electrode 21, this structure forming a distributor means for the fluid to be treated. As shown clearly in the upper part of Fig. 4 the annular passage 30 is decidedly curved downward at the outer 130

part so that a flow of emulsion passing therefrom will be directed adjacent the surface of the electrode of highest field intensity. The discs 23 are provided with comparatively sharp annular edges 32.

Attached to the upper end of the shell 11 immediately below the top 12 is an annular member 34 which provides an annular trough 35, this trough 35 connecting to the interior of the shell 11 through an annular mouth 36. Emulsion is supplied to the trough 35 by means of an emulsion pipe 37. The mouth 36 of the trough 35 is adapted to direct emulsion along the inner face of the shell 11. The inner face of the shell 11 has flanges 38 extended inward therefrom, the inner edges of the flanges providing annular edges 39 adjacent which the field is concentrated so that the field is more intense adjacent the annular edges 39 than immediately around the electrode 17.

At the upper end of the treater immediately below the cover 12 is a barrier fluid supply pipe 40 which is connected to a pipe 41. The barrier fluid supply pipe 40 is annular and is provided with a multiplicity of small openings 42. Supported by suitable arms 44 immediately below the supply pipe 40 is a deflector plate 45.

In Fig. 1 the numeral 47 represents a transformer, one side of the secondary of which is connected by a conductor 48 to the conductor rod 16 and the other side of the secondary of which is connected to the shell 11 by a conductor 49. The shell 11 and the emulsion supply pipe 20 is grounded, as indicated at 50.

The operation of the invention is substantially as follows:

The barrier fluid supply pipe 40 is adapted to supply a dielectric fluid to the treating spaces 52 and 53 which exist between the electrode 21 and the electrode 17 and between the shell 11 and the electrode 17. Any suitable dielectric fluid may be used, but for the purpose of convenience and because of its desirable qualities I prefer to use a dry oil. The dry oil is sprayed downward through the small openings 42 and is deflected by the deflector 45 so that it will flow on opposite sides of the live electrode 17 in the treating spaces 52 and 53. The dry oil provides dielectric barriers in these treating spaces as indicated at 55 and 56 in Fig. 1. A continuous flow of dry oil is conducted at all times when the dehydrator is in operation so that the dielectric barrier will be maintained at all times. The dry oil may be withdrawn with the treated emulsion through an outlet pipe 57 which is provided in the bottom 18.

Emulsion is supplied to the emulsion inlet pipe 20, flowing from the upper end thereof through the openings 29 and the annular passage 30. As previously explained, the annular passage 30 directs the emulsion downward adjacent the surfaces of the electrode

21. The emulsion is directed substantially as indicated by arrows 58 of Fig. 4.

I prefer to use a material such as plaster of Paris for the electrode because of the fact that it has an affinity for water and therefore tends to hold the wet emulsion thereto as the emulsion passes downward from the upper end thereof, thus acting as an emulsion guide. This makes it possible to accomplish a thorough and satisfactory treatment of the emulsion and prevents the dielectric shield from being destroyed by a mixture with the emulsion. It is not absolutely essential to have the central electrode 21 formed with a surface of this material but it is desirable because better results may be obtained. Experiments have been made using an ordinary electrode for the central electrode and fairly good results have been obtained, but better results are often obtained when the electrode has a surface of a material such as plaster of Paris.

The emulsion being directed along the surfaces of the electrode 21 hangs thereto as indicated by dotted lines 59 in Fig. 1. By the time the emulsion reaches the lower end of the electrode it has been thoroughly treated and the water content thereof is agglomerated into masses which are of sufficient size to gravitate from the oil when it is delivered to a separating tank. The treated emulsion is taken from the dehydrator through the outlet pipe 57.

Emulsion is also supplied through the pipe 37 to the trough 35. This emulsion is directed by the mouth 36 along the inner surface of the shell 11 as indicated by dotted lines 60 of Fig. 1. This emulsion flows downward to the lower part of the shell 11 and is thoroughly treated in its passage through the treating space 53. This treated emulsion is also withdrawn through the pipe 57. The dehydrating action which takes place will now be explained.

The dehydrating action which takes place in the treating space 53 is substantially the same as that which takes place in the treating space 52; therefore, it is thought to be sufficient to explain only the action taking place in the treating space 52.

A high electric potential is maintained between the electrodes of the treater. The shell 11 and the central electrode 21, being grounded, are at ground potential, and the live electrode 17 is a very high potential. The electrode 21, since it is in the center, is the electrode of highest field intensity. This is because of the fact that the electric field spreads radially therefrom to the live electrode 17. The emulsion directed along the electrode 21 is therefore subjected to the action of that portion of the field which is of maximum intensity. As the emulsion flows downward, as indicated by the arrows 58, it is treated by the electric field and the particles of water

are coalesced. As previously explained, dehydrating action takes place by reason of a bombardment of water particles in the emulsion by means of charged particles of water (or other electrolyte) which are shot outward from the electrode. The central electrode 21 is provided with annular edges 32 which form zones of extremely high potential gradient. As indicated in the lower part of Fig. 4 water masses 62 moving downward along the surfaces of the electrode 21 pass outward onto the discs 23 and when they reach the edges 32 thereof, they pass into the extremely high potential gradient field and certain thereof are discharged violently outward, being broken up into small charged particles as indicated at 63. These small charged particles 63 strike against other bound charges in the treating space 52 and cause a coalescing by reason of the bombarding action and also by reason of the fact that the charged particles 63 may be of a different charge than the particles with which they come in contact. As the lower end of the electrode 21 is reached the emulsion is completely treated and the water particles are all agglomerated into masses of sufficient size to gravitate from the oil when the mixture of water and oil is delivered to a separating tank.

The dielectric barrier 55 provides a shield which prevents the chaining of water particles across the two electrodes. Although the flow of dielectric fluid and emulsion is shown as taking place downward, it may be reversed and passed upward through the shell. This dielectric is important to the invention since it entirely eliminates short-circuiting and prevents an excessive current from being drawn, and by so doing permits the emulsion to be readily treated. My invention is particularly adapted for treating very wet emulsions which cannot be treated in the ordinary dehydrator because of the short-circuiting characteristics of the oil. In my invention all short-circuiting is prevented; consequently the wet emulsions may be successfully treated.

I have found that in some instances it is not necessary to provide the dielectric barriers 55 and 56. This is probably due to the fact that the attraction between the electrode 21 and the wet emulsion is so great that the wet emulsion and also the masses of water will hang to the electrode 21, whereas the dry or de-emulsified oil will move in the treating space to a position near the live electrode 17. This in effect is the same as the barrier of dry oil and differs only in that the barrier is not formed from a separate oil but is formed from oil which has been de-emulsified.

In the drawings I have not shown the inner face of the treater 11 and the flanges 38 which form a grounded electrode as being

formed of a material having an affinity for the emulsion. It should be understood that if desirable this may be done and falls within the scope of the invention.

The edges 32 and 39 are an important auxiliary feature of the invention because they provide very high potential gradient field zones which cause an augmented discharge of the small charged particles into the treating space. These edges are not in all cases essential, however, and successful treating, but to a somewhat reduced degree, can also be accomplished with electrodes having no sharp edges 32 and 39. A treater having a smooth inner electrode, is shown and claimed in my co-pending application Serial No. 203,253, filed July 2, 1927. As previously explained these zones accelerate the dehydration of emulsion.

It should be noted particularly that in my invention the central electrode 21 which is the electrode of highest field intensity is grounded. This is reverse to standard practice and is an important part of the invention since it has certain novel features. By grounding the central electrode 21 it is possible to extend the emulsion inlet 20 therethrough and to direct the emulsion along the surface of the electrode without any danger whatsoever to the operator who regulates the oil feed, or without the complicated system of insulated reservoirs, tanks, inlet pipes, etc., which would otherwise be necessary. If the central electrode 21 was made the high tension electrode, according to standard practice, the feed pipe 20 which is at ground or earth potential could not be connected thereto. If desired the central electrode may be the live electrode, suitable insulation being provided.

In Fig. 5, I show a modified form of the invention which is more or less an extension of the idea of the form shown in Fig. 1. The form shown fragmentarily in Fig. 5 consists of a central grounded electrode 100, an intermediate grounded electrode 101 and a shell 102 which serves as an outer grounded electrode. Supported by a conductor 103 which is equivalent to the conductor 16 of Fig. 1 is a frame structure 104 which supports an inner live electrode 105 and an outer live electrode 106, the electrodes 105 and 106 being placed between the grounded electrodes 100, 101 and 102. Emulsion is supplied adjacent the face of the central grounded electrode 100 by means of an annular passage 108 formed at the upper end thereof. Emulsion is supplied to the opposite faces of the intermediate grounded electrode 101 by an emulsion supply pipe 109 which has orifices 110 and 111. Emulsion is supplied to the inner face of the shell 102 by means of an annular trough 113. The central electrode 100 is provided with edges 115 by means of which extremely high potential fields may be obtained. The inter-

mediate electrode 101 is provided with edges 116 which extend inward and edges 117 which extend outward, thus forming areas of high field intensity in the treating spaces on each side thereof. Edges 119 are provided on the shell 102 for obtaining the same effect. It should be noted that the spaces between the pairs of electrodes gradually decrease as the outside is reached. As the electrodes are increased in diameter the normal field intensity at the active treating surface and edge is decreased, but by making the treating spaces narrower the desirable potential gradient is maintained. It is possible in carrying out the scheme of the invention to provide any number of concentric electrodes. For practical purposes, however, at the present time it is thought that the form of the invention shown in Fig. 1 is most satisfactory and most economical in its treatment of emulsions.

Certain modifications of the basic idea and structure disclosed herein are also shown and claimed in certain co-pending applications. For instance, my application Serial No. 203,253 supra discloses a system utilizing the basic principles herein disclosed, but one which differs in providing a high velocity method of introduction, as well as in providing a novel dielectric circulating system and a novel shape of electrode. Similarly, in my co-pending application Serial No. 143,933, filed October 25, 1926, I have disclosed an electric treater and a novel process whereby charged particles of a charging fluid are introduced into the fluid to be treated. Various other co-pending applications show the basic principles herein disclosed in combination with other structures, the claims therein being directed to the modified combinations and methods rather than to the broad structure and methods herein disclosed.

I claim as my invention:

1. In a dehydrator of the class described, the combination of: a primary electrode; and a secondary electrode, one of said electrodes being provided with an emulsion guide formed of material having an affinity for the emulsion.
2. In a dehydrator of the class described, the combination of: a primary electrode; a secondary electrode; and means for directing an emulsion to be treated along the surface of one of said electrodes, said electrode along which said emulsion is directed being provided with an emulsion guide formed of material having an affinity for said emulsion.
3. In a dehydrator of the class described, the combination of: a primary electrode; a secondary electrode; means for directing an emulsion to be treated along the surface of one of said electrodes, said electrode along which said emulsion is directed being provided with an emulsion guide formed of material having an affinity for said emul-

sion; and a dielectric barrier between said emulsion and the other of said electrodes.

4. In a dehydrator of the class described, the combination of: a live electrode; a grounded electrode; means for directing an emulsion to be treated along the surface of one of said electrodes, said electrode along which said emulsion is directed being provided with an emulsion guide formed of material having an affinity for said emulsion, said electrode along which said emulsion is directed having means for establishing zones of maximum field potential gradient; and a dielectric barrier between said emulsion and the other of said electrodes.

5. In an apparatus for dehydrating petroleum emulsions, the combination of: an electrode surrounded by a layer of the emulsion to be treated; and means for surrounding said layer of emulsion with a moving fluid envelope of higher dielectric strength than said emulsion.

6. In an apparatus for dehydrating emulsions the combination of: an electrode having a central opening; a second electrode projecting into said opening; means for supplying emulsion to be treated to the space immediately adjacent to said second electrode, said emulsion flowing along said second electrode; and means for maintaining a dielectric barrier between said emulsion and said first mentioned electrode.

7. In an apparatus for dehydrating petroleum emulsions, the combination of: an electrode surrounded by a layer of the emulsion to be treated; a sheath formed about and forming a part of said electrode, said sheath having an affinity for said emulsion so as to retain said emulsion close to said electrode; and means for surrounding said layer of emulsion with a moving fluid envelope of higher dielectric strength than said emulsion.

8. In an apparatus for dehydrating petroleum emulsions, the combination of: an electrode surrounded by a layer of the emulsion to be treated; and a sheath formed about and forming a part of said electrode, said sheath having an affinity for said emulsion so as to retain said emulsion close to said electrode.

9. In combination in an electric treater: a pair of electrodes at a primary potential; an intermediate electrode between said pair of electrodes, said intermediate electrode being at a secondary potential, there being treating spaces between said intermediate electrode and each of said pair of electrodes adapted to contain a fluid to be treated; and means for directing a flow of dielectric barrier fluid adjacent each side of said intermediate electrode.

10. In an electric treater of the class described, the combination of: a primary electrode having a surface thereon adapted to

- hold a flow of fluid to be treated in contact therewith; relatively sharp ledges extending a distance from said surface, said ledges being formed of a material having an affinity 5 for said fluid to cause said fluid to cling thereto when flowing along said electrode; a secondary electrode; and means for establishing a potential difference between said electrodes.
- 10 11. In an electric treater, the combination of: a pair of electrodes; means for establishing an electric potential between said electrodes, said electrodes being so constituted or arranged as to establish an electric field of 15 non-uniform intensity therebetween; and means for passing a dielectric barrier fluid through only that portion of the field which is of low intensity.
12. A method of treating an emulsion, 20 which includes the steps of: setting up an electric field between concentric electrodes; moving the emulsion to be treated in said electric field in the form of a relatively thin fluid envelope along, in contact with, and 25 around the central of said concentric electrodes whereby said fluid envelope is subjected to the action of the most intense portion of said electric field; and maintaining a body of fluid of higher dielectric 30 strength than the emulsion to be treated in that portion of said field adjacent the outer of said concentric electrodes.
13. A method of treating a fluid by means 35 of an electric field established between a pair of electrodes, one of which provides a body with a ledge thereon extending toward the other electrode, which method includes the step of passing a relatively thin stream of fluid along said electrode having said 40 ledge and in contact therewith, said stream of fluid following outward around said ledge and returning inward toward the body of said electrode without breaking contact with the surface of said ledge.
- 45 14. In an electric dehydrator, the combination of: primary and secondary electrodes between which is established an electric field of non-uniform intensity, that portion of the field adjacent said primary electrode being more intense than that portion of the field adjacent said secondary electrode; and means for directing a stream of the 50 emulsion to be treated adjacent the surface of said primary electrode and into the most intense portion of said field.
15. In a dehydrator, the combination of: a central electrode having an opening formed longitudinally therethrough; a surrounding electrode around said central electrode; means for establishing an electric 55 field between said electrodes; means for supplying a fluid to said opening of said central electrode; and distributor means associated with said central electrode for forming said fluid passing through said open- 60
- ing into a fluid envelope surrounding said central electrode.
16. A combination as defined in claim 15 in which said central electrode is grounded. 70
17. In a dehydrator, the combination of: a central electrode having an opening formed longitudinally therethrough; a surrounding electrode around said central electrode; means for establishing an electric field between said electrodes; means for supplying a fluid to be treated to one end of said opening of said central electrode, said fluid flowing therethrough in a given direction; and distributor means at the other end of 75 said central electrode and communicating with said opening for discharging said fluid in the form of a fluid envelope surrounding and in contact with the surface of said central electrode, said distributor means discharging said fluid envelope in a direction substantially opposite said given direction. 80
18. In an electric treater, the combination of: a central grounded electrode; a live electrode around said central electrode and defining a treating space therearound, said live electrode being electrically insulated from said grounded electrode; and distributor means electrically connected to said central electrode for introducing fluid into said 85 treating space and adjacent said central electrode in the form of a fluid envelope moving therealong. 90
19. In a treater, the combination of: a primary electrode comprising a plurality of spacer members, and discs separating adjacent spacer members and extending therebeyond; and a secondary electrode spaced from said primary electrode. 95
20. In a treater, the combination of: a primary electrode comprising a plurality of sleeves, a disc between adjacent sleeves, and supporting means extending through said sleeves and discs; and a secondary electrode spaced from said primary electrode. 100
21. In an electric dehydrator, the combination of: a central electrode; a surrounding electrode; means for impressing a difference in potential between said electrodes; and a distributor means associated with said central electrode for supplying an envelope of fluid around and in contact with the surface of said central electrode, said distributor means being at the same potential as said central electrode. 105
22. In an apparatus for dehydrating a petroleum emulsion, the combination of: means including a pair of spaced electrodes for setting up an electric field which is much more intense adjacent the surface of one of said electrodes than adjacent the surface of the other; and an emulsion guide positioned on said electrode adjacent which the field is more intense and having an affinity for said emulsion for retaining thereagainst the emulsion to be treated. 110
- 125
- 130

23. A method of treating a petroleum emulsion by the use of a pair of electrodes so constituted or arranged as to be capable of establishing an electric field therebetween of 5 greater intensity adjacent one of said electrodes than adjacent the other, which method includes the steps of: impressing a potential difference across said electrodes to set up said electric field; circulating in the more intense portion of said field a stream of emulsion; and simultaneously circulating in a less intense portion of said field a fluid of higher dielectric strength than said emulsion in said stream.
- 10 24. A method of treating a petroleum emulsion containing water particles dispersed in oil and by the use of an electric field formed between concentric electrodes so constituted or arranged as to set up a field therebetween which is much more intense adjacent one electrode than adjacent the other, which method includes the steps of: moving concentric envelopes of said emulsion and a fluid of higher dielectric strength through said field to agglomerate said dispersed water particles, the envelope of emulsion being closest to the electrode adjacent which the field is most intense; removing the treated emulsion from between said electrodes before material separation of said agglomerated water particles from said oil.
- 20 25. A method of treating an emulsion by the use of a field established between a pair of electrodes so constituted or arranged as to establish an electric field of non-uniform intensity thereacross, the field adjacent one of said electrodes being much more intense than adjacent the other of said electrodes, which method includes the steps of: impressing a potential difference across said electrodes to set up said electric field of non-uniform intensity; and circulating in said electric field and longitudinally along the electrode adjacent which said field is most intense, a stream of the emulsion to be treated, said stream of said emulsion flowing in contact with said electrode adjacent which said field is most intense and being of insufficient thickness to completely bridge said electrodes.
- 30 26. In a dehydrator, the combination of: a central electrode of small diameter; means for establishing an electric field around said central electrode, said field being highly concentrated immediately adjacent the surface of said central electrode; and a distributor means for circulating a fluid to be treated in said field and forming a fluid envelope of said fluid flowing smoothly along and immediately around said central electrode so as to pass through the most intense portion of said field and adjacent a body of liquid of higher dielectric strength than said fluid to be treated
- 35 and which is positioned in a lower intensity portion of said field.
27. A method of treating a petroleum emulsion including a continuous oil phase and a dispersed water phase by the use of central and surrounding electrodes, which includes the steps of: establishing a difference in potential between said electrodes to set up an electric field therebetween of extremely high intensity immediately adjacent said central electrode and of much lower intensity adjacent said surrounding electrode; forming a portion of said emulsion in the form of a fluid envelope engaging the external surface of said central electrode; moving said fluid envelope longitudinally along and in contact with said central electrode for a material portion of its length to agglomerate said dispersed water phase; and moving said fluid envelope away from said central electrode and into a settling zone wherein said agglomerated water phase settles from said oil phase.
- 40 28. A method of treating involving the use of two liquids one of lower dielectric strength than the other, which method includes the steps of: establishing an electric field of non-uniform intensity; subjecting the liquid of lower dielectric strength to the action of the more intense portion of the electric field; and maintaining the liquid of higher dielectric strength in a portion of the field of lower intensity.
- 45 29. In an electric treater, the combination of: a grounded shell; a sleeve-shaped electrode insulated from and positioned in said shell; a small central electrode extending axially into said sleeve-shaped electrode; means for establishing a difference of potential between said central and said sleeve-shaped electrode and between said sleeve-shaped electrode and said shell whereby fields are set up therebetween, the field between said central and said sleeve-shaped electrode being highly concentrated immediately around said central electrode; and means for introducing fluid into only the most intense portion of said concentrated field and immediately adjacent said central electrode whereby said fluid may flow through the most intense portion of said concentrated field without bridging said central and said sleeve-shaped electrode.
- 50 30. In an electric dehydrator, the combination of: an electrode having a surface which has a selective affinity for water over oil and which terminates in a sharp edge at which there is a concentrated electric field; and means for delivering water particles to said surface in such a manner that they are violently projected from said edge by said concentrated field.
- 55 In testimony whereof, I have hereunto set my hand at Los Angeles, California, this 10th day of September, 1926.
- 60 HARMON F. FISHER.
